US00D817760S

(12) **United States Design Patent** (10) **Patent No.:** **US D817,760 S**
Petrosino et al. (45) **Date of Patent:** **** May 15, 2018**

(54) **MAGNETIC CAP**

(71) Applicant: **INTEGRATED LINER TECHNOLOGIES, INC.**, Rensselaer, NY (US)

(72) Inventors: **Paul M. Petrosino**, Schoharie, NY (US); **James M. Crouch, Jr.**, Castleton, NY (US); **Lenny Diaz**, Clifton Park, NY (US)

(73) Assignee: **Integrated Liner Technologies, Inc.**, Rensselaer, NY (US)

(**) Term: **15 Years**

(21) Appl. No.: **29/592,932**

(22) Filed: **Feb. 3, 2017**

(51) LOC (11) Cl. **09-07**

(52) U.S. Cl.

USPC **D9/452**; D24/127

(57) **CLAIM**

The ornamental design for a magnetic cap, as shown and described.

DESCRIPTION

FIG. 1 is a perspective view of a first embodiment of the magnetic cap of the present design;

FIG. 2 is a second perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a perspective view of a second embodiment of the magnetic cap of the present design;

FIG. 10 is a second perspective view thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a right side elevation view thereof; and,

FIG. 16 is a left side elevation view thereof.

The broken lines shown in the figures represent features that form no part of the claimed design.
